CLAIM

The ornamental design for a draw tape bag, as shown and described.

DESCRIPTION

FIG. 1 is a perspective view of a draw tape bag showing our new design;

FIG. 2 is a front view of the draw tape bag of FIG. 1, the back side being a mirror image thereof;

FIG. 3 is a right side view of the draw tape bag of FIG. 1, the left side being a mirror image thereof;

FIG. 4 is a top view of the draw tape bag of FIG. 1;

FIG. 5 is a bottom view of the draw tape bag of FIG. 1; and, FIG. 6 is a sectional view taken along the lines 6-6 as indicated in FIG. 1.

The broken lines showing environmental structure are for illustrative purposes only and form no part of the claimed design.
